UNITED STATES PATENT OFFICE.

STANLEY W. NICHOLSON, OF TOLEDO, OHIO, ASSIGNOR, BY MESNE ASSIGNMENTS, TO THE DURA COMPANY, OF TOLEDO, OHIO, A CORPORATION OF OHIO.

WINDOW-CONTROL MECHANISM.

Application filed January 7, 1924. Serial No. 684,869.

The invention relates to a window control mechanism and is particularly applicable to vehicles. One of the objects of the invention is the provision of a mechanism which is so arranged that the force applied therethrough for raising or lowering a window is applied longitudinally of the window and substantially in the longitudinal median line of the same. Another object is the provision of a mechanism which is compactly arranged and which provides a leverage which is greater than that secured by a lever of the same length as the mechanism. Further objects of the invention reside in the novel features of construction and combinations and arrangements of parts as more fully herein-after set forth.

In the drawing:

Figure 1 is an inside elevation of a vehicle door with the lining removed and showing a window control mechanism embodying my invention;

Figure 2 is a cross section on the line 2—2 of Figure 1.

1 is the door of a motor vehicle having in its upper portion the opening 2 and in its lower portion the pocket 3. 4 is the window or closure vertically slidable in guideways in the hinge and lock pillars of the door frame, and 5 is the lockboard extending between these pillars.

To raise and lower the window 4, I have provided mechanism in the pocket 3 of the door and operatively connected to the window 4 at the middle of the channel 6 embracing its lower edge. This mechanism is so arranged that the force applied therethrough is substantially in a vertical plane. In detail, 7 and 8 are like levers which are pivotally mounted at their inner ends upon the hinge pillar of the door frame. These levers converge toward each other from their pivotal mountings and their outer ends are pivotally connected to the arm 9, which latter extends from the outer ends of the levers towards their inner ends and is pivotally connected at 10 to the middle of the channel 6 embracing the lower edge of the window. With this arrangement the pivot 10 remains at all times in substantially the vertical plane passing through the longitudinal center of the window owing to the fact that the swinging movement of one lever will compensate for the swinging movement of the other le-

ver. However, to allow a slight variation 55 from the vertical plane through the center of the window sufficient play is allowed for the pivot.

The mechanism is raised and lowered by suitable means, which in the present instance 60 comprises the screw 11 engaging the nut 12 swivelled upon the lower arm 8 and driven from suitable gearing in the gear case 13, which latter is mounted upon the lockboard 5. 14 is a coil spring for counterbalancing 65 the window and also the levers and arm of the window control mechanism.

To provide a unit mounting for the levers and the counterbalancing spring of the window control mechanism, I have provided 70 the support 15 which is secured to the hinge pillar of the door frame by suitable mechanism such as the screws 16. The upper and lower ends of this support have ears 17 and 18 through which extend the pivots for connecting the inner ends of the upper and lower levers 7 and 8 to the support. The coil spring 14 is also secured to the upper end of the support 15, the lower end of this coil spring being secured to the lower lever 8.

From the above description it will be readily seen that I have provided a window control mechanism which is so arranged that its point of connection to the window travels substantially through a vertical plane passing through the longitudinal median line of the window owing to the fact that the point of pivotal connection between the pair of levers and the arm travel through arcs which compensate for each other. It will also be seen that the leverage secured with my construction is decidedly greater than that secured by a lever of the same length as my mechanism. Furthermore, that I have provided a unit mounting for the levers and 85 counterbalancing spring of the mechanism.

What I claim as my invention is:

1. The combination with a frame and a closure slidable in said frame, of a pair of similar levers extending transversely of the path of travel of said closure and pivotally mounted upon said frame, and an arm pivotally connected to said levers and operatively connected to said closure, said arm extending from its point of pivotal connection with said levers toward the point of pivotal mounting of said levers and being operatively connected to said closure.

2. The combination with a frame and a closure slidable in said frame, of a support upon said frame, a pair of levers pivotally mounted upon said support, an arm pivotally connected to the free ends of said levers and operatively connected to said window, and a counterbalancing spring connected to said support and one of said levers.

3. The combination with a frame and a closure slidable in said frame, of a pair of levers extending transversely of the path of travel of said closure and pivotally mounted upon said frame, a device operatively connected at spaced points to said levers and also operatively connected to said closure, said device being angularly movable upon movement of said levers whereby the point of connection between said device and closure moves in a substantially straight line, and

means for actuating one of said levers and thereby actuating said device and closure.

4. The combination with a frame and a closure slidable in said frame, of a pair of levers extending transversely of the path of travel of said closure and pivotally mounted upon said frame, a triangularly-shaped device having its base portion operatively connected at spaced points to said levers and being pivotally connected to said closure at its apex, said device being angularly movable upon movement of said levers whereby the point of connection between said device and closure moves in a substantially straight line, and means for actuating one of said levers and thereby actuating said device and closure.

In testimony whereof I affix my signature.

STANLEY W. NICHOLSON.
